UNITED STATES PATENT OFFICE.

THOMAS G. GOWEN, OF BOONVILLE, INDIANA.

MEANS FOR PREVENTING WHIPPING OUT OF ENDS OF FLAGS.

1,270,813.

Specification of Letters Patent.

Patented July 2, 1918.

Application filed September 6, 1917. Serial No. 189,924.

To all whom it may concern:

Be it known that I, THOMAS G. GOWEN, a citizen of the United States, residing at Boonville, in the county of Warrick and State of Indiana, have invented certain new and useful Improvements in Means for Preventing Whipping Out of Ends of Flags; and I do hereby declare the following to be a full, clear, and exact description of the invention, such as will enable others skilled in the art to which it appertains to make and use the same.

This invention is in the nature of an improvement in flags and the object of the invention is to provide means whereby a flag will be prevented from "whipping" in the wind, and thus tearing the outer end.

With this object in view the invention consists in the improved construction, arrangement and combination of parts of and for attachment to flags, which will be herein-after fully described and afterward particularly claimed.

In order that the construction and operation thereof may be readily comprehended, I have illustrated an approved embodiment of my invention, with modifications thereof, in the accompanying drawings and will now proceed to fully describe the same in connection with said drawings in which—

Figure 1 represents a United States flag on a pole extended as by the wind, and equipped with my invention;

Fig. 2, a fragmentary view showing a small part of the outer end of the flag of Fig. 1, on an enlarged scale, parts being shown in dotted lines;

Fig. 3, a fragmentary sectional view on an enlarged scale on a vertical plane parallel with the outer end of the flag;

Fig. 4, a fragmentary sectional view on a horizontal plane cutting through the flag near the outer end thereof;

Fig. 5, a view similar to Fig. 2, of a slight modification of the structure illustrated.

Like reference characters denote the same parts in all of the figures of the drawings.

Referring particularly to the drawings 7 indicates a U. S. flag comprising the usual starry field 8, and the thirteen red and white stripes 9 and 10.

At the outer ends of the stripes, and consequently of the flag, I have constructed

pockets 11, on each stripe on one side of the flag, and similar pockets 12, on each stripe on the other side of the flag, as shown in Figs. 1, 2, 3 and 4, although I may omit the pockets on one side or the other of the flag 60 if desired.

These pockets extend longitudinally of the flag and are open to the wind at the ends toward the inner or pole end of the flag and closed on their other three sides.

In the modification of Fig. 5, I provide two pockets, as at 13 and 14, on each red and white stripe on each side of the flag.

At 18 I show eyelets at suitable points in the inflated parts to facilitate drainage of 70 such parts in the event that they become flooded by heavy rains.

It will be observed that all of the pockets are located at the outer end of the flag and are open toward the pole to catch the wind and thus to become inflated and form, as it were, wind bags. The whipping of a flag in the wind somewhat resembles the cracking of a whip, and tears the end of the flag. It is obvious that inflated pockets, or wind bags, cannot crack or pop like a whip lash and consequently, by means of my construction, the flag is saved from whipping or cracking and consequently from tearing out or damaging the outer end.

By means of the inflated pockets I present a resistance to the wind, thus creating tension in the flag between the extreme loose end and pole or fastened end, and as the force of the wind varies, this tension automatically varies, thus preventing the loose end of the flag from doubling back to or against the side thereof, and whipping out as the wave passes out to the end of the flag.

All the pockets contemplated by me will 90 be made of the same material and color as the stripes upon which they are placed, whereby the appearance of the flag will not be marred.

It will be obvious that other changes and 100 modifications may be made in the make up of my invention, without departing from its spirit, so long as such changes or modifications fall within the scope of the claims.

Having thus fully described my invention, what I claim as new, and desire to secure by Letters Patent of the United States, is—

1. A flag provided with a pocket at its outer end, closed on all sides except that fac- 110

ing toward the wind when the flag is hoisted, whereby said pocket will be inflated by the wind.

2. A flag provided with a series of pockets 5 extending across its outer end, said pockets being open toward the inner or pole end of the flag and closed on all other sides.

3. A flag provided with a series of pockets 10 extending across its outer end, said pockets being open toward the inner or pole end of the flag and closed on all other sides, each of said pockets being located upon one of the red and white stripes of the flag.

4. A flag provided with a series of pockets 15 extending across its outer end, said pockets being open toward the inner or pole end

of the flag and closed on all other sides, each of said pockets being located upon one of the red and white stripes of the flag, and there being two pockets upon each of said 20 stripes.

5. A flag provided with a pocket at its outer end comprising a tube extending along a stripe of the flag and open toward the inner or pole end of the flag. 25

In testimony whereof I have signed my name to this specification in the presence of two subscribing witnesses.

THOMAS G. GOWEN.
